(57) **CLAIM**

The ornamental design for door shelf, as shown and described.

DESCRIPTION

FIG. 1 is a perspective view of a door shelf showing a second embodiment of my new design;

FIG. 2 is a front elevational view thereof;

FIG. 3 is a left side elevational view thereof;

FIG. 4 is a right side elevational view thereof;

FIG. 5 is a top elevational view thereof;

FIG. 6 is a back elevational view thereof; and,

FIG. 7 is bottom elevational view thereof.

The broken line showing is for illustrative purposes only and forms no part of the claimed design.
